US00D956960S

(12) **United States Design Patent** (10) **Patent No.:** **US D956,960 S**
(45) **Date of Patent:** **** Jul. 5, 2022**

(54) **AUTOINJECTOR**

- (71) Applicant: **Phillips-Medisize A/S**, Struer (DK)
- (72) Inventors: **Carsten Petersen**, Højbjerg (DK); **Emil Wegger Jensen**, Viby J (DK); **Troels Rask Pedersen**, Egå (DK)
- (73) Assignee: **Phillips-Medisize A/S**, Struer (DK)
- (**) Term: **15 Years**
- (21) Appl. No.: **29/753,847**
- (22) Filed: **Oct. 2, 2020**
- (51) LOC (13) Cl. **24-02**
- (52) U.S. Cl. **USPC D24/113**
- (58) **Field of Classification Search**
USPC D24/112–114, 133, 186, 127–131, 144;
D19/115–123, 177, 193
CPC A61M 5/3156; A61M 5/31591; A61M 5/3155; A61M 5/3157; A61M 5/24; A61M 5/31501; A61M 5/31551; A61M 5/31585

(57) **CLAIM**

The ornamental design for an autoinjector, as shown and described.

DESCRIPTION

FIG. 1 is a front perspective view of an autoinjector showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front perspective view of a second embodiment of an autoinjector showing our new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof; and,

FIG. 16 is a bottom view thereof.

The broken lines immediately adjacent to the shaded areas represent the bounds of the claimed design and form no part thereof. The broken lines depicting the remainder of the autoinjector form no part of the claimed design.

1 Claim, 8 Drawing Sheets
